UNITED STATES PATENT OFFICE

2,210,859

DEVICE FOR FACILITATING THE CLOSING
OF BAGS AND OF SIMILAR CONTAINERS

Friedrich Schäfer, St. Gallen, Switzerland

Application November 26, 1937, Serial No. 176,619
In Switzerland June 12, 1936

4 Claims. (Cl. 229—65)

My invention relates to improvements in closing devices for paper bags and similar containers in which the top edge of the bag, together with an individual stiffening band, is clamped fast and folded up so as to seal the bag; and the objects of my improvement are, first, to provide facilities for easily and readily sealing the bag in an effective way and manner; second, to design a type of closing device which is cheaply and readily manufactured in great quantities; and, third, to provide such a type of closing device which easily and readily may be bent into any form desired.

The use of flat metallic strips as stiffening inserts for the purpose of clamping and holding fast the closing flap of the top edges of paper bags and similar containers is known. A serious disadvantage of these latter strips, however, is that they cannot be bent into any form desired.

20 I attain the objects set forth above by the device illustrated in a plurality of forms of invention in the accompanying drawing, in which—

Fig. 1 is a closing device in the form of a wire bent into wave shape; Fig. 2, a closing device 25 in the form of a stiffening strip comprising a paper-wrapped wire bent according to Fig. 1; Fig. 3, a cross-section of Fig. 2; Fig. 4, a closing device according to Fig. 2, bent to an angle in the longitudinal sense; Fig. 5, a cross section of 30 the latter figure; Fig. 6, a closing device according to Figs. 4 and 5 fastly mounted upon a bag, in elevation; and Fig. 7, a cross-section of the latter.

In Fig. 1, *w* is a wave-shaped piece of wire bent 35 in one plane. This wire may serve as an individual marginal stiffening truss to be inserted into the closing flap or top fold of a bag when folding and closing up the latter. The ends of the said truss may be bent back upon the closed bag as in the case of the marginal stiffening 40 inserts in the form of metal strips known heretofore.

In Figs. 2 and 3 a zig-zag shaped wire 'a' is wrapped or enveloped in paper or any other 45 fibrous material *c* so as to form a closing strip, which at *b* is provided with a gummed sealing edge. This form of invention possesses the additional advantage that the gummed surface *b* is subdivided by means of the wire *a* into a series 50 of gummed portions, whereby a wide and resistant stiffening band is obtained.

This latter band also may be wrapped up in the top fold or ply of the bag when folding up and closing the latter. The wrapped portion also, e. 55 g., may be given a zig-zag shape. One, furthermore, may use a short piece of the said band in the way of a clamp or clip for sealing the throat of the bag in a manner well known.

The ends of a strap, moreover, may be fastened

to the ends of the said stiffening band *c* for the purpose of enabling one to carry the bag suspended from one's arm.

Figs. 4 and 5 show a marginal stiffening strip *e*, comprising a zig-zag shaped wire *f* and a paper-envelope *e* for the latter, the said strip at *d* being folded over or creased so as to form an angle-shaped structure.

After mounting the said strip onto the top edge of a bag, both the strip and the edge may be 10 bent, e. g., in S-shape.

As the top edge of the bag and the said stiffening strip after compression are fastly held together and thus hermetically seal the bag, the latter cannot be readily opened. For this latter 15 purpose, however, the marginal stiffening strip on one side of the bag is extended beyond the wall of the bag, so that one may take a hold of the strip and pull it upward, upon which the bag is 20 opened.

In the last form of invention, as illustrated in Figs. 6 and 7, the marginal stiffening strip *k*, angle-shaped in cross-section and comprising the wave-shaped wire insert *i*, is 25 clamped fast to the top edge *l* of the bag, and only may be removed by bending back and upwardly one of the legs of the stiffening strip.

What I claim and desire to secure by Letters Patent is:

1. A device for facilitating the closing of bags and of similar containers comprising a piece of wire bent closely in one plane in a wave or zig-zag shape so as to form a band of some width and of a substantially greater length than the width of the bag; the said band snugly embedded in 35 the top fold of the bag upon folding down the latter, and the ends of the said band bent back upon the folded top portion of the bag.

2. A device of the character described and according to claim 1, and in which the said band 40 is wrapped in and secured to an envelope made of fibrous material.

3. A device of the class described and according to claim 1, and in which the said band additionally is bent or creased lengthwise so as to 45 form the legs of an angle; the latter put over the closed mouth of the bag, and the ends of the said band bent back upon the folded top portion of the bag.

4. A device of the class described comprising 50 a piece of wire bent in one plane into close corrugations so as to form a band with parallel top and bottom and of a substantially greater length than the width of the bag, and an envelope made of fibrous material in which the said band is 55 wrapped and to which the said band is glued; the whole being bent or creased lengthwise so as to form the two legs of an angle.

FRIEDRICH SCHÄFER.
